UNITED STATES PATENT OFFICE

152,600

DESIGN FOR A COMBINATION SAW AND CLEAVER

Paul F. Danielson, San Marino, Calif.

Application February 10, 1948, Serial No. 144,384

Term of patent 14 years

(Cl. D22—3)

To all whom it may concern:

Be it known that I, Paul F. Danielson, a citizen of the United States, residing at San Marino, in the county of Los Angeles and State of California, have invented a new, original, and ornamental Design for a Combination Saw and Cleaver, of which the following is a specification, reference being had to the accompanying drawing, forming part thereof.

In the drawing:

Fig. 1 is a top plan view of a combination saw and cleaver, showing my new design;

Fig. 2 is a side elevation thereof, and

Fig. 3 is an end elevation of the combination saw and cleaver looking in the direction of the arrow 3 of Fig. 2.

I claim:

The ornamental design for a combination saw and cleaver, as shown,

PAUL F. DANIELSON.
